DISPENSING CONTAINER

William A. Ringler, Wayne, Pa., assignor to National Folding Box Company, New Haven, Conn., a corporation of New Jersey

Application October 19, 1938, Serial No. 235,725

6 Claims. (Cl. 206—57)

This invention relates to dispensing containers and more particularly to a dispensing container formed from paperboard material adapted for the dispensing of interleaved sheets.

5 Articles of merchandise such as toilet tissue, paper towels, paper napkins and facial tissues are generally packed and sold in lots of one hundred or more sheets which are folded and interleaved together so that the withdrawal of one sheet will 10 expose the free end of the next succeeding sheet so that it can be readily grasped and withdrawn from the stacked pile of sheets. Such stacked interleaved sheets are generally packaged in a shipping carton or container from which they are 15 removed and then inserted into a permanent dispenser which forms no part of the original carton in which the interleaved stack of sheets is packed. A satisfactory and economically constructed interleaved sheet-dispensing device, 20 which could serve both as a shipping carton and a dispensing device and which can be so economically made as to permit the same to be discarded after the sheets have been dispensed therefrom, has long been sought.

25 It is an object of this invention to provide an improved dispensing container for interleaved sheets, in which the interleaved sheets may be packed and shipped and from which the sheets may be separately dispensed as desired, which 30 dispensing container can be economically manufactured and packed substantially entirely by automatic machinery, at a cost which compares favorably with the cost of manufacturing and packaging paperboard cartons for this purpose which 35 do not possess the dispensing feature.

Another object of this invention is to provide 40 an improved paperboard dispensing container having a suspension hanger associated therewith whereby the container may be conveniently suspended from one or more wall hooks while the sheet contents are being dispersed therefrom.

Still another object of this invention is to provide 45 an improved dispensing container formed from a single blank of paperboard material in which sheeted articles of merchandise, such as toilet tissue, paper towels, paper napkins and facial tissues, may be packaged and contained during shipment and storage and from which such sheeted articles may be individually dispensed.

50 Another object of this invention is to provide an improved container formed from a single blank of paperboard material having a hanger device associated therewith by which the container may be hung in suspended position for

display or dispensing purposes, the hanger device having means associated therewith for locking the container closure in closed position.

Other objects of this invention will become apparent as the disclosure proceeds.

5 In accordance with my invention an improved dispensing container is provided formed from a single blank of paperboard material into which the interleaved sheets arranged in stacked relationship may be inserted during the assembly of 10 the container, the container further being provided with a hanger device by means of which the container may be held in suspended position while the interleaved sheets are individually dispensed and withdrawn through a dispensing slot 15 or opening provided in the bottom section thereof. The front and rear wall sections of the paperboard container are each provided with bottom-forming sections hinged thereto. When these bottom-forming sections are turned inwardly in substantial alignment, they have a 20 combined width sufficient to substantially close the lower end of the container. When the bottom-forming sections are arranged in downwardly inclined gable-forming position they define a 25 convenient dispensing slot therebetween. A pair of foot tabs extend from the adjacent lower end of each of the side wall sections, which tabs are turned inwardly and secured to the bottom-forming sections in such a manner as to support the 30 two bottom-forming sections in downwardly inclined gable-forming position. This container is particularly adapted for the dispensing of relatively stiff paper sheets, such as paper towels as well as softer or more pliable sheets, such as 35 toilet and facial tissues.

40 My improved dispensing container is provided with a hanger device which comprises a hanger flap extending upwardly and hinged to the rear wall section and a downturned hanger flap hinged to the first-named hanger flap, through which hanger flaps one or more suspension apertures are provided. The double-ply hanger device provides a strong and sturdy hanger support for the container and its contents. A closure flap is 45 hinged to the front wall section, which is of a size to substantially cover the top end of the container. The closure flap is provided with a tuck-in flap hinged thereto which extends into the container. The hanger device is provided with a locking tab adapted to be inserted into an elongated slot provided in the closure flap to lock the closure flap in closed position.

50 Various other features and advantages of the invention will be apparent from the following 55

particular description and from an inspection of the accompanying drawings.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawings forming a part thereof, in which

Fig. 1 is a plan view of a prepared blank from which my improved dispensing container is formed;

Fig. 2 is a perspective view of the container as it appears after the sheet material to be dispensed therefrom has been inserted therein;

Fig. 3 is a perspective view of the packed container showing the container closure flap partially assembled in container-closing position;

Fig. 4 is a perspective view of the upper portion of the packed container as it appears when fully assembled and closed ready for suspension upon suitable wall hooks;

Fig. 5 is an enlarged vertical cross-sectional view of the container, showing more particularly the elongated dispensing opening in the bottom section thereof;

Fig. 6 is a vertical cross-sectional view through the fully assembled container as it appears when in sheet-dispensing position;

Fig. 7 is a fragmentary perspective view of the blank shown in Fig. 1 as it appears when partially assembled into container form;

Fig. 8 is a fragmentary perspective view of the lower portion of the container as it appears when fully assembled ready to dispense sheet material therefrom; and

Fig. 9 is a fragmentary perspective view of the bottom portion of the container as it appears when collapsed for shipment.

Similar reference characters refer to similar parts through the drawings and the specification.

This dispensing container is particularly adapted for the dispensing of paper sheets, such as paper towels and the like, but may also be used for dispensing lighter and more pliant interleaved sheets, such as paper tissue. This container may be economically formed from a single blank of paperboard material, as illustrated in Fig. 1, comprising a rear wall section 31 and a front wall section 32 joined together by a side wall section 33 along the score lines 34. A side wall section 35 hinged to the front wall section 32 along the score line 36 is adapted to be secured to a securing flap 37 hinged to the rear wall section 31 along the score line 38 as by staples *b* or by a suitable adhesive; thus to provide a tubular container body.

A closure flap 11 hinged to the front wall section 32 along the score line 38, is provided to form a closure for the top of the container. The closure flap 11 is of such width and length as to substantially cover the top end of the container body when placed in container-closing position. Top end flaps 13 hinged to each of the side wall-forming sections 33 and 35 along the score lines 39 are provided, which are turned inwardly so as to overlie the open end of the container after the sheet contents have been packed therein. The closure flap 11 is provided with a tuck-in flap 15 which is hinged thereto along the spaced score lines 16, and when the container is assembled is tucked inwardly so as to lie adjacent the inside

face of the rear wall section 31. A cut line 17 joins the spaced score lines 16, the cut 17 being somewhat arcuate in shape so that when the tuck-in flap is inserted inwardly of the container, a lug portion 18 cut out from the closure flap 11 extends upwardly and defines a slit opening 19 between the tuck-in flap 15 and the adjacent free edge of the closure flap 11.

A convenient hanger device 20 connected to the rear wall section 31 of the container blank 10 is provided, from which the container may be held in suspended position from one or more wall hooks, so that the sheet contents may be conveniently dispensed. The hanger device comprises a hanger flap 21 hinged to the upper end of the rear wall section 31 along the score line 38, and a downturned hanger flap 23 hinged to the hanger flap 21 along the score line 24, so as to provide a double ply paperboard hanger. One or more holes or openings 29 are provided in hanger flap 21 with which corresponding holes or openings 30 provided in the downturned hanger flap 23 align to provide hook-receiving openings 20 in the hanger device.

Means associated with the hanger device are provided for locking the closure flap 11 in closed position, which means comprises an inturned flap 25 hinged to the inturned hanger flap 23 along the score line 26, the inturned flap 25 lying between the inside face of the rear wall section 31 and the tuck in flap 15 of the closure 11 when the container is in closed assembled position. A locking tab 28 cut out from the inturned flap 25 by the cut line 27 therein is arranged to be inserted into the slit 19 so as to overlie the lug projection 18 and the tuck-in flap 15 of the closure flap 11, to lock the closure 11 in closed position.

The container formed from the blank shown in Fig. 1 is provided with a novel bottom construction, which constitutes an important feature of this invention. As shown in Figs. 5, 6 and 8, the bottom construction of the container is of generally gable-shape when in dispensing position. Projecting from the lower edges of both the rear wall section 31 and the front wall section 32, is a gable-forming flap 40 hinged to the respective rear and front wall sections 31 and 32 along the score line 41. Each of the gable flaps 40 is provided with an inturned flap 42 hinged thereto along the score line 43 so as to provide a double ply bottom construction, as illustrated in Fig. 6. Projecting from the lower end of each of the side wall sections 33 and 35 are a pair of foot tabs 46 and 47 which are separated by an end slot 51. Each of the foot tabs 46 and 47 are traversed by a pair of spaced diagonally extending score lines 48 and 51, which meet and terminate at the meeting point of the body defining score lines 34, 38 and 41. Score lines 48 and 51 define therebetween a triangular section 50, which is adapted to fold inwardly as illustrated in Fig. 9. The score lines 48 define the slope or camber given to the gable flaps 40 when the container is in dispensing position, as shown in Fig. 8, whereas the score lines 51 define the lower edge of the side wall sections 33 and 35 when the gable flaps 40 are arranged in collapsed shipping position, as illustrated in Fig. 9.

The dispensing container is assembled from the blank shown in Fig. 1 by securing the securing tab 37 to the free edge of the side wall section 35 so as to provide a tubular body construction comprising rear wall section 31, front wall section 32 and connecting side wall sections 33 75

and 35. Foot portions 47 extending from the end of side wall sections 33 and 35 are then inserted inwardly in position to overlie the inside face of the gable flap 40 hinged to the front wall section 32. Care should be taken so that the gable fold line 48 therein substantially coincides with the free ends 40' of the gable flap 40. Flap 42 is then inturned, as shown in Figs. 6 and 9, so as to overlie the inside face of the gable flap 40 and the foot tabs 47. It will be noted that the end portions 44 of the flap 42 are cut away substantially the thickness of the paperboard comprising the foot tabs 47. Staples b or other securing means extending through the gable flap 40, 5 the foot tabs 47 and the inturned flap 42 are provided for securing these parts firmly together as illustrated in Fig. 11. It will be noted that the 10 triangular portions 50 of the foot tabs 47 are free and unsecured to the gable flap 40, so that 15 these parts may fold inwardly, as shown in Fig. 9, when the bottom is in collapsed position. These triangular portions 50 also provide tension supports for the ends of the gable flaps 40 when 20 arranged in downwardly inclined dispensing position, as shown in Figs. 5 and 6.

The foot tabs 46 are also inserted inwardly so 25 as to overlie the inside face of the gable flap 40 hinged to the rear wall section 31, the foot tabs 46 being so arranged that the gable-defining score line 48 substantially coincides with the free 30 ends 40' of the gable flap 40. Flap 42 is then inturned so as to overlie the inside face of the gable flap 40 and the foot tabs 46. Staples b or other securing means extending through the 35 gable flap 40, foot tabs 46, and the inturned flap 42 are provided to secure these parts firmly together. The ends 44 of the flap 42 are cut away substantially the thickness of the paperboard forming the foot tabs 46 so as to provide room 40 therefor.

The bottom construction thus formed comprises two inwardly extended gable flaps, one hinged to the front wall section 32 and the other hinged to the rear wall section 31, the ends of 45 these flaps defined by the score lines 43 being separated a distance sufficient to provide a convenient dispensing slot s therebetween when arranged in downwardly inclined dispensing position. The slot ends s' extending upwardly into 50 the side wall sections 33 and 35, which end slots 55 separate the foot tabs 46 and 47, form in effect a continuation of the dispensing slot s when the container is assembled. The end slots s' provide a convenient opening into which the finger or 60 other instrument may be inserted to facilitate ejection of the interleaved sheets in event the lowermost sheet cannot be conveniently grasped through the slot opening s. The hinged triangular portions 50 of the foot tabs 46 and 47 65 provide tension devices which serve to hold the gable flaps 40 in downwardly inclined dispensing position.

When the sheet contents have been packed 65 into the container, the container may be sealed by turning the end flaps 13 hinged to the side wall sections 33 and 35 along the score lines 39 inwardly. The closure flap 11 hinged to the front wall section 32 along the score line 38 is then folded inwardly and the tuck-in flap hinged 70 to the closure flap 11 along the score line 16 is tucked inwardly into the container. The hanger device 20 is assembled by folding the inturned hanger flap 23 along the score line 24 over its 75 companion hanger flap 21 which is hinged to the rear wall section 31 along the score lines 38.

Tuck-in flap 25 hinged to the hanger flap 23 along the score line 26 is then inserted into the container so as to lie between the rear wall section 31 and the tuck-in flap 15. Locking tab 28 is substantially simultaneously folded over the 5 lug portion 18 and inserted into the elongated slot 19 provided in the closure flap 11, thus 10 securely holding the closure flap 11 in closed position, thus completing the packaging and sealing of the container.

A plurality of filled containers formed from the blank shown in Fig. 1 may be conveniently stacked in a minimum of space due to the fact that the gable flaps 40 may be pressed towards the contents so as to lie substantially perpendicular to the front wall section 32 and rear wall section 31 with both gable flaps 40 lying in substantially the same plane and substantially closing the bottom end thereof. The triangular portions 50 of the foot tabs 46 and 47 will then 15 fold inwardly, as illustrated in Fig. 9, so that a substantially flat bottom for the container is provided. Furthermore, the hanger flaps 21 and 23 may be folded inwardly, so as to overlie the closure flaps 11 along the fold lines 38 and 20 25 26, so that a substantially rectangular package is provided.

When the sheet contents are to be dispensed, the container may be conveniently suspended from a pair of wall hooks by means of the suspension device 20. The gable flaps 40 will have a tendency to spring outwardly so as to lie in a downwardly inclined position, defining a dispensing slot s therebetween. It has been found that certain sheets of paper material of a relatively heavy nature, such as paper towels, can be dispensed in a highly satisfactory manner when packaged in a container having a gable-shaped bottom constructed as above described. The gabled bottom is unusually strong and sturdy 35 40 in construction. The smooth calendered surface of the inturned flaps 42 and the rounded edges defined by the fold lines 43, facilitate the convenient and positive ejection of the separate interleaved sheets as they are drawn therefrom. 45 While this container is particularly adapted for the dispensing of stacked interleaved paper towels, the same may be used and is adapted for the dispensing of other interleaved sheet material.

The dispensing container herein disclosed is economical in paperboard, can be formed, packed and assembled substantially entirely by automatic machinery at relatively low cost. The container lends itself readily to attractive decoration, and may be made of any desired size suitable to house and contain the stacked interleaved sheets.

While certain novel features of the invention have been disclosed herein and are pointed out 60 in the annexed claims, it will be understood that various omissions, substitutions and changes may be made by those skilled in the art without departing from the spirit of the invention.

What is claimed is:

1. A dispensing container for interleaved sheets formed from a single blank of paperboard material including, a rear wall section, a front wall section, side wall sections joining said front and rear wall sections, a bottom wall 70 having a sheet dispensing slot therein, said slot continuing a limited distance into said side wall sections whereby to partially expose the ends of the adjacent interleaved sheets, each of said side wall sections having a pair of spaced tabs 75

extending therefrom for supporting the bottom wall, said bottom wall comprising a flap hinged to each of said front and rear wall sections, each of said tabs having fold lines extending 5 transversely thereacross defining a fold portion and a free end portion, means for securing said front and rear wall flaps to the free ends of the adjacent tabs to normally retain said front and rear wall flaps in downwardly 10 inclined position, the fold portions of said tabs being foldable so as to permit the arrangement of said bottom-forming flaps in position substantially in the same plane during shipment and storage of the container.

15 2. A combined shipping and dispensing container for interleaved sheets formed from a single blank of paperboard material including, a rear wall section, a front wall section, side wall sections joining said front and rear wall sections, a bottom wall having a dispensing slot 20 therein through which said interleaved sheets may be separately withdrawn, tabs extending inwardly from said side wall sections for supporting said bottom wall, said bottom wall comprising a bottom forming flap hinged to each of 25 said front and rear wall sections, means for securing said tabs to said front and rear wall flaps to support said front and rear wall flaps in downwardly extending gable formation providing a dispensing slot therebetween, said tabs being foldable to permit said front and rear wall flaps when in shipping position to be arranged 30 in substantially the same plane with the meeting edges of said front and rear wall flaps substantially closing said dispensing slot.

35 3. A shipping and dispensing container for interleaved sheet material formed from a single blank of paperboard material including, a tubular body portion comprising a rear wall section, a front wall section, and side wall sections 40 joining said front and rear wall sections, a bottom forming flap hinged to each of said front and rear wall sections, a pair of tabs extending from the lower end of each of said side wall sections, means for securing said tabs to said 45 front and rear wall flaps to support said flaps in gable-shaped formation defining a dispensing slot therebetween, said tabs being foldable when the container is in shipping position whereby said bottom-forming flaps may be positioned to 50 lie in substantially the same plane and close to said dispensing slot.

4. A prepared paperboard blank from which a dispensing container may be formed including, a front facing section, a rear facing section, a side section hingedly connected along its side edges to said facing sections, and a second side section hingedly connected along one side edge to the adjacent side edge of one of said facing 55 sections, and a bottom forming construction for assembly into gabled formation including, a pair of spaced similar securing tabs hingedly connected to the lower end of each of said side wall sections along a pair of downwardly inclined converging score lines, a slot forming notch cut into each of said side wall sections at the lower end thereof, each of said notches extending 60 between the tabs of the respective pairs and into

said side wall section beyond the converging score lines, and an exterior gable forming flap having a width greater than the width of the adjacent tabs hinged along the score line to the lower edge of each of said facing sections, each 5 of said score lines having its ends terminating adjacent the upper ends of the adjacent converging score lines when the blank is assembled, and an inturned overlying flap hinged to each of said exterior flaps having a length less than 10 the length of the exterior flap to which it is hinged.

5. A dispensing container for interleaved sheets formed from a single blank of paperboard material including, a rear wall section, a front wall section, side wall sections joining said front and rear wall sections, each of said side wall sections having a pair of spaced tabs 15 extending from one end thereof, each of said tabs having a plurality of fold lines extending 20 transversely thereacross, defining a fold portion and a free end portion, and a bottom-forming flap hinged to each of said front and rear wall sections, one of the tabs extending from each of said side wall sections having the free 25 end portion thereof turned inwardly and secured to said front wall flap and the other of said tabs extending from each of said side wall sections having the free end portion thereof extending inwardly and secured to said 30 rear wall flap, said fold portions being operative to support said front and rear wall flaps in downwardly inclined position providing a gable-shaped formation and defining a dispensing opening therebetween, said tabs being foldable whereby said bottom-forming flaps may be positioned 35 to lie in substantially the same plane and at substantial right angles to said front and rear wall sections.

6. A dispensing container for interleaved sheets formed from a single blank of paperboard material including, a rear wall section, a front wall section, side wall sections joining said front and rear wall sections, each of said side wall sections having a pair of spaced tabs 40 extending from one end thereof, each of said tabs having a plurality of fold lines extending 45 transversely thereacross defining a fold portion and a free end portion, and a bottom-forming flap hinged to each of said front and rear wall sections, one of the tabs extending from each 50 of said side wall sections having the free end portion thereof turned inwardly and secured to said front wall flap and the other of said tabs extending from each of said side wall sections having the free end portion thereof extending 55 inwardly and secured to said rear wall flap, said fold portions being operative to support said front and rear wall flaps in downwardly inclined position providing a gable-shaped formation, the fold portions of said tabs being foldable inwardly to permit inward collapse of said bottom-forming flaps whereby said bottom-forming flaps may be positioned to lie in substantially the same plane and at substantially right angles to said front and rear wall sections.

WILLIAM A. RINGLER.
